United States Patent

Des. 242,021
Patented Oct. 26, 1976

242,021

TISSUE DISPENSER

Donald J. Shanklin, Granada Hills, Calif., assignor to
Orion Industries, Inc., Torrance, Calif.

Filed Nov. 29, 1974, Ser. No. 528,422

Term of patent 14 years

Int. Cl. D9—03

U.S. Cl. D9—224

Fig. 1

Fig. 2

Fig. 3

Fig. 4

Fig. 5

FIG. 1 is a perspective view of a tissue dispenser showing my new design;

FIG. 2 is a rear elevational view;

FIG. 3 is a rear elevational view partially broken away and partially in section;

FIG. 4 is a bottom plan view; and

FIG. 5 is a top plan view thereof.

I claim:

The ornamental design for a tissue dispenser, substantially as shown and described.
